CLAIM

The ornamental design for cabinet handles, as shown and described.

DESCRIPTION

FIG. 1 is a perspective view of a first handle.

FIG. 2 is a front view of the handle shown in FIG. 1; and, FIG. 3 is a partial side elevational view and sectional view drawn for purposes of illustration.

The broken line(s) which define the bounds of the claimed design form no part thereof.

1 Claim, 2 Drawing Sheets

FIG. 1

FIG. 2
